Inventor

Harley E. Goodwin.

UNITED STATES PATENT OFFICE

HARLEY E. GOODWIN, OF HARTFORD, CONNECTICUT

GAME

Application filed November 28, 1930. Serial No. 498,715.

This invention comprehends certain new and useful improvements in games, and relates particularly to that class of game which has to do with the throwing or projecting 5 of a ball, and the catching or receiving of the same.

The primary object of the invention is to provide a game device of simple and novel construction, whereby a resilient net is used 10 to project a ball, and the same net employed to catch or receive the ball, and novel means for holding the net in position so as to adroitly project and catch the ball, thus providing an interesting and useful game of 15 skill.

A further object is to devise a game which may be generally played out of doors, engaging two or several players in healthful exercise, promoting quickness of eye and judgment of distance as well as general dexterity.

A further object is to provide a game in which the ball is volleyed forth and back between the players in some semblance to 25 the game of tennis, but without the use of the customary tennis-net and enclosed court, and the score and penalties may be similar or of the players own devising. In general, and for example, the player A will, with- 30 out projecting the ball too wide or too high, strive to make B miss catching the ball in the net, and in that event B will be penalized a determined number of points which will accrue to A.

Another object of the invention is to provide a game which may be played without recourse to a special field, course or court, being adaptable to any fair-sized yard, lot or lawn, and without other equipment than the 40 net device itself and one or more balls preferably of soft rubber.

With these and other objects in view, the invention consists in the construction and novel combination of parts hereinafter fully described, illustrated in the accompanying drawing and pointed out in the claims here-to appended; it being understood that various changes in the form, proportion, size and minor details of construction within the 50 scope of the claims may be resorted to with-

out departing from the spirit or sacrificing any of the advantages of the invention.

For a full understanding of the invention, reference is to be had to the following description and accompanying drawing in 55 which: Fig. 1 is a perspective view of a combination of net and holder or frame, to which the net is attached, and the device is shown in position to be stretched backward in order to project a ball. Fig. 2 is likewise a perspective view of a net in a substantially horizontal position, attached to a somewhat modified form of frame or holder, and Fig. 3 shows the net in drooping or relaxed form suitable for catching or receiving a ball, the 60 net being attached to a modified form of frame or holder. In general, the net is identified by the numeral 7 and is formed of a plurality of resilient strands running generally lengthwise, these, particularly in Fig. 65 1 and 3 having association with a series of strands running circularly, which strands may, or may not be of a resilient nature. The net is generally tapering, especially when extended or about to be extended, and is de- 70 signed to be open at its forward end, where it is attached to a rim portion of a frame or holder, this rim being designated by the nu- 75 meral 8.

The net tapers rearward to an apex and in 80 the various figures is shown as being attached to a cup-shaped terminal portion designed to hold a ball. However, it will be understood that the net itself may be so shaped as to form an apex provided with suitable reinforcing means, and this terminal portion or apex is indicated by the numeral 9.

In Fig. 2 a form of net is shown having a series of resilient strands running longitudinally and indicated by numerals 10—11— 90 12—13—14 and 15, and these may be directly attached to the series of strands running circularly and forming a network from the rim 8 to the apex 9, or may be ranged over or underneath this network, as far as the purpose of the device is concerned viz., to project and receive a ball.

As shown in Fig. 1, the frame for holding the net has handle members 16, a grip 17 attached thereto, the handle members extend- 100

ing downward and rearwardly and terminating in a cross member 18, for engaging and resting upon the arm as a support and to steady the device in use.

5 In Fig. 2 a modified form of handle means is shown, wherein the handles 19, run generally straight, having a modified form of grip 20 between the handles, and a flexible arm engaging band 21 at the ends of the handles.

10 In Fig. 3, a further handle modification is indicated in a generally vertical grip 22, branches 23 extending backward and having at their ends a member 24, to rest upon and engage the arm.

15 Having thus described the invention, what I claim and desire to protect by Letters Patent is:—

1. A game device including a net adapted to catch a ball, closed at one end and open at 20 the other end, a frame to which the forward end of the net is connected, and handle means associated with the frame and including a grip adapted to be grasped by a hand, and an arm engaging member adapted to engage the 25 arm.

2. A game device including a net adapted to catch a ball, closed at one end and open at the other end, a frame to which the forward end of the net is connected, and handle means 30 associated with the frame and including a grip adapted to be grasped by a hand, and an arm engaging member adapted to engage the arm, said net having associated therewith resilient means whereby the ball is propelled when the net is stretched and then released.

3. In a game device for catching and throwing a ball, including a generally tapered net having a means to which the open larger end of the net is connected, said means being 40 provided with a hand grip, said net being associated with resilient means which are extended when the net is pulled out, and which propel the ball when the net is released, and means on said device acting independently of said grip and arranged to bear against a support to effect resistance to force applied to said net to stretch it.

4. A game device adapted to project and receive a ball, consisting of a generally tapered net entirely closed at one end and entirely open at the other end, the open end being attached to a frame having a handle means which has associated therewith a hand grip and an arm engaging member, said net 50 having resilient strands extending generally in the direction of the length of the net.

5. A game device for projecting and receiving a ball, consisting of a tapering net closed at one end and open and unobstructed at the 60 other end, the open end being attached to a frame having a handle means and an arm engaging member, the net being formed of resilient strands and intended to be pulled out and then released thereby projecting a ball.

6. A game device for catching and throwing a ball, comprising a tapered resilient net, formed small and closed at one end and relatively large and open at the other end, a frame to which the larger end of the net is attached, a handle means depending from the frame, a hand grip associated with the handle means and an arm engaging member connected with the handle means for adding stability to the device while same is held in position for projecting or catching a ball.

7. A game device for throwing and receiving a ball, including a tapering resilient net, the larger end of which is attached to a frame, and having at its smaller end an apex or pocket, for holding a ball, said frame having a depending handle means with which is connected a hand grip, and an arm engaging member, one modification of this member being a flexible band engaging the forearm to assist in holding the device steady while projecting or receiving a ball.
